CLAIM

The ornamental design for a vest, as shown and described.

DESCRIPTION

FIG. 1 is a front elevational view of a vest showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines in FIGS. 1 and 2 represent the portion of the design that forms no part of the claim.
